UNITED STATES PATENT OFFICE.

JULIUS E. BOMBERG, OF DETROIT, MICHIGAN.

MOLDING-MACHINE.

1,343,386.

Specification of Letters Patent. Patented June 15, 1920.

Application filed February 14, 1919. Serial No. 276,931.

To all whom it may concern:

Be it known that I, JULIUS E. BOMBERG, a citizen of the United States of America, residing at Detroit, in the county of Wayne 5 and State of Michigan, have invented certain new and useful Improvements in Molding-Machines, of which the following is a specification, reference being had therein to the accompanying drawings.

The invention relates to machines for forming molds and has for one of its objects the provision of an efficient and durable construction, in which the molding table is moved through an endless circuit 15 and comprises a series of pivotally connected plates. Another object of the invention is the provision of rotating means directly engaging the plates to move the table through an endless circuit. A further object is the provision of means for automatically raising the mold flasks from the plates after the molds have been formed. Other objects of the invention reside in the novel arrangements and combinations of parts as 25 more fully hereinafter set forth.

In the drawings:

Figure 1 is an end elevation of the construction embodying my invention with part of the molding table removed;

Fig. 2 is a side elevation thereof;

Fig. 3 is a central vertical longitudinal section therethrough.

The frame of the machine comprises the base 1 having the standards 2 at its sides. 35 3 is the molding table for carrying the mold flasks, and 4 is the tamping mechanism. The molding table is continuous and comprises the series of plates 5 pivotally connected to each other at their side edges. These plates 40 pass around and are mounted upon the pairs of disks 6 at the ends of the machine, the disks having each of their edges substantially equal to the width of the inner side of each plate. The disks engage the opposite ends of the plates, which are provided with inwardly-extending flanges 7 adapted to lie adjacent the inner sides of the disks and thereby prevent transverse movement of the plates relative to the disks.

50 For rotating the molding table 3, the following mechanism is provided: 8 is a power shaft mounted in the upper ends of the standards 2 and having at its ends suitable belt pulleys 9. The power shaft is provided 55 with cranks 10 outside the standards 2, the pins of which are connected to the upper

ends of the links 11, the lower ends of which are, in turn, pivotally connected to the outer ends of the links 12 rotatably mounted at their inner ends upon the main shaft 13. 60 This shaft is rotatably mounted on the base 1. A dog 14 is pivotally mounted upon each link 12 intermediate its ends, this dog adapted to engage teeth in a gear 15 non-rotatably mounted on the shaft 13. A 65 spring 16 is provided for yieldably forcing the end of each dog into engagement with the teeth. Non-rotatably mounted upon opposite ends of the shaft 13 are the driving gears 17, the teeth of which mesh 70 with the teeth upon gears 18, which are non-rotatably mounted upon shafts 19 on opposite ends of the base 1. The disks 6 are secured upon opposite ends of the shafts 19 and inside the base 1.

75 The tamping mechanism 4 comprises the straps 20 upon the eccentrics 21, which eccentrics are non-rotatably mounted upon the power shaft 8. The straps 20 are longitudinally adjustable and, as shown, each comprises two parts, 22 and 23, adjustably secured to each other by means of the bolts 24, which engage in a longitudinal slot in the member 22. The lower end of the member 23 is pivotally secured to the plunger bar 25, which slidably engages at its opposite ends the vertical guide-ways 26 in the standards 2. Suitably mounted on the under surface of this plunger bar are the plungers 27 and 28 for forcing the material for forming the molds, such as molding sand, into the flasks upon the plates 5.

80 Patterns 29 are permanently secured to each molding plate 5 and each molding plate is further provided with the pairs of guide-pins 30 for receiving the cope and drag, 31 and 32 respectively, which form the coöperating parts of the molding flask, the arrangement being such that the cope and drag surround their respective patterns. The plunger 27 is adapted to force the sand down into the cope 31 and the plunger 28 is adapted to force the sand into the drag 32, but in the latter case the bottom 33 for the drag is placed between the plunger 28 and drag so that the plunger contacts with this bottom and forces the latter against the molding sand.

85 100 105 110 With the construction as thus far described, upon power being applied to the power shaft 8, the latter will be rotated, thereby rocking the dogs 14 through the

intermediate cranks 10, links 11, and the links 12. These dogs in their upward movement engage the teeth of the gears 15 and in their return movement slide thereover so that the gears will be rotated by a step-by-step motion. These gears in turn transmit the motion to the disks 6 through the main shaft 13, gears 17 and 18 and shafts 19. The dogs 14 are rocked a distance such that the disks 6 are rotated through one quarter of a revolution so that the molding table advances the distance of the width of one plate at a time. The cope and drag 31 and 32 respectively are placed on the plate 5 at one end of the table and the molding material placed therein during the time the table is at rest. The table then advances one plate and the plungers 27 and 28 move downwardly to force the sand against and around the patterns upon the plate. Meanwhile, another cope and drag are being placed upon the succeeding plate and filled with molding material. The table then advances another plate and the cope and drag are ready to be removed at the opposite end of the table, and another plate is ready to receive another cope and drag with the molding material, the tamping mechanism meanwhile acting upon the intermediate plate molds.

For automatically raising the cope and drag when they reach the removal end of the table, the following construction is provided: 34 is a cross bar extending between the standards 2 and underneath the upper plates 5 of the table, the ends of this cross bar adapted to guide and support the plate thereabove when the plungers 27 and 28 move downward. 35 are longitudinally-extending bars secured at one end to the cross bar 34 and mounted at their opposite ends upon the frame 36 which has bearings 37 engaging the shaft 19 at the removal end of the machine. 38 is a bifurcated rock bar centrally pivoted upon the member 39 depending from the cross bar 40 secured to the bars 35. The inner end of this rock bar is preferably recessed to receive the lower end of the vertically extending rod 41 which extends up through an aperture in the cross bar 34 and terminates slightly below the lower surface of the plate 5 thereabove. The opposite end of the rock bar 38 has the furcations 42, the ends of which engage in the bar 43 extending transversely of the machine with sufficient play to permit of the relative movement between the furcation ends and bar when the former are rocked. Mounted on opposite ends of the bar 43 are the vertical stems 44 which pass up through bearings 45 on the frame 36. The upper ends of these stems are secured to the cross connection of the H-shaped frame 45^a, which extends across the frame 46. This frame is mounted upon the inner side of each plate

5 and is free to move toward or from the same. Specifically brackets 47 are provided extending in from the plates and having lateral portions 48 extending across the frame 46 at points outside the H-shaped frame 45^a. 70 Pins 49 are adjustably secured in the frame 46 as by threadedly engaging the same and slidably engage in apertures in the plates 5, the arrangement being such that the outer ends of these pins simultaneously engage a 75 cope and a drag to raise the same from the plate upon which they rest. The rod 50 is provided adjustably secured to the plunger bar 25 as by threadedly engaging the same, this rod being in alinement with the vertically-extending rod 41. The plates 5 each have the hole 51 therethrough which is located so that it will be in alinement with the rod 50 when its plate is under the plunger bar, thereby permitting the rod 50 85 to engage the rod 41 when the plunger bar moves downwardly. This raises the stems 44 and their H-frames 45 which in turn move the frames 46 upwardly with their pins 49 to lift the cope and drag. 90

What I claim as my invention is:

1. In a molding machine, the combination with a frame, of an endless series of plates pivoted to each other and movably mounted on said frame, said plates forming a continuous molding table and an endless conveyor. 95

2. In a molding machine, the combination with a continuous molding table comprising a series of plates, of rotating means 100 directly engaging the sides of said plates for moving said table through an endless circuit.

3. In a molding machine, the combination with a frame, of shafts rotatably mounted in said frame, disks non-rotatably secured to said shafts, a series of pivotally-connected plates engaging on said disks, and means for rotating said shafts. 105

4. In a molding machine, the combination with a frame, shafts rotatably mounted in 110 said frame, and disks non-rotatably secured to said shafts, of a table comprising a series of pivotally-connected plates extending around and engaging the edges of said disks, said edges each being of a length substantially equal to the width of one of the plates. 115

5. In a molding machine, the combination with a molding table, of a cope and drag mounted on the same side of said table, and a single plunger for simultaneously pressing the molding material into said cope and drag. 120

6. In a molding machine, the combination with a molding table carrying a flask, of 125 means for pressing the molding material into said flask, and means extending through said molding table for subsequently automatically raising said flask from said table.

7. In a molding machine, the combination 130

with a molding table carrying a plurality of mold flasks, of means for pressing the molding material into one of said flasks, and means operated by said first-mentioned means for raising another of said flasks from said table.

8. In a molding machine, the combination with a molding table, comprising a series of pivotally connected plates, each adapted to 10 carry a mold flask, of means carried on the inner sides of said plates movable therethrough into engagement with said mold flasks, means for pressing the molding material into one of said flasks, and means operated by said pressing means for actuating 15 said first-mentioned means to separate a flask from its plate.

9. In a molding machine, the combination with a frame, of shafts rotatably mounted 20 in said frame, disks non-rotatably secured to said shafts, a series of pivotally-connected plates engaging said disks, and flanges on said plates adapted to engage said disks for preventing the transverse movement of said 25 plates relative to said disks.

10. In a molding machine, the combina-

tion with a frame, of a molding table movable through an endless circuit and comprising a series of plates each adapted to carry a mold flask, means for pressing molding material into one of said mold flasks, and a cross bar on said frame beneath the plate on which said mold flask is mounted, said cross bar provided with means for supporting 35 said plate.

11. In a molding machine, the combination with a rotatable shaft, of a polygonal member non-rotatably secured to said shaft, a series of pivotally connected plates engaging said polygonal member, and means 40 for rotating said shaft.

12. In a molding machine, the combination with a frame, of a continuous molding table movably mounted thereon, a plurality of molding flask sections adapted to be 45 mounted thereon and conveyed thereby, and means for simultaneously pressing the molding material into said sections at one point in their travel.

In testimony whereof I affix my signature. 50

JULIUS E. BOMBERG.
